(57) **CLAIM**

The ornamental design for a horizontal rings vase, as shown and described.

DESCRIPTION

FIG. 1 is a perspective view of an embodiment of the clear walled vase incorporating my new design;

FIG. 2 is a front view thereof;

FIG. 3 is a rear view thereof;

FIG. 4 is a right view thereof;

FIG. 5 is a left view thereof;

FIG. 6 is a top end thereof;

FIG. 7 is a bottom view thereon; and

FIG. 8 is a cross-sectional view taken along the line 8-8 of FIG. 2 and viewed in the direction of the arrows.

FIG. 9 is a perspective view of an alternate embodiment of an opaque walled vase incorporating my invention.

FIG. 10 is a front view of the vase of FIG. 9;

FIG. 11 is a rear view of the vase of FIG. 9;

FIG. 12 is a right view of the vase of FIG. 9;

FIG. 13 is a left view of the vase of FIG. 9;

FIG. 14 is a top view of the vase of FIG. 9;

FIG. 15 is a bottom view of the vase of FIG. 9; and

FIG. 16 is a cross-sectional view taken along the line 16-16 of FIG. 10 and viewed in the direction of the arrows.

FIG. 17 is a perspective view of a second alternate embodiment of a translucent walled vase incorporating my invention.

FIG. 18 is a front view of the vase of FIG. 17;

FIG. 19 is a rear view of the vase of FIG. 17;

FIG. 20 is a right view of the vase of FIG. 17;

FIG. 21 is a left view of the vase of FIG. 17;

FIG. 22 is a top view of the vase of FIG. 17;

FIG. 23 is a bottom view of the vase of FIG. 17; and,

FIG. 24 is a cross-sectional view taken along the line 24-24 of FIG. 18 and viewed in the direction of the arrows.
